UNITED STATES PATENT OFFICE.

MILTON G. VOLCKER, OF HUNTINGTON, INDIANA.

GASOLINE-DISPENSING TANK.

Application filed July 14, 1924. Serial No. 726,036.

This invention relates to means for dispensing the contents of receptacles in predetermined quantities. More particularly the invention is directed to improved means of this nature designed particularly for application to gasoline dispensing tanks of the automobile service station type.

The principal purpose of the invention is to provide a gasoline tank equipped with dispensing means capable of selective manual setting to release all or variable predetermined quantities of the tank contents, dependent on the particular setting selected; said dispensing means being arranged to automatically terminate flow of gasoline from the tank upon releasement of the desired quantity thereby providing for absolute accuracy of measurement of any desired amount of gasoline without having to depend upon the guess work or judgment of the attendant.

A further purpose of the invention is to place the tank dispensing means under the control of a series of keys in such manner that the simple act of securing the proper key in depressed position will automatically effect discharge of the desired quantity of gasoline from the tank without requiring further attention on the part of the attendant.

Other purposes and advantages of the invention, as well as the details of construction and operation will be more readily apparent from a consideration of the following description taken in connection with the accompanying drawings, in which

Fig. 1 is a view in side elevation of a tank equipped with my invention.

Fig. 2 is a fragmentary sectional view showing the interior construction of one of the outlets together with the means for controlling the valve normally closing the outlet.

Fig. 3 is a view showing one of the outlets in horizontal section.

Fig. 4 is a top plan view of one of the outlets, and

Fig. 5 is a fragmentary view showing the arrangement of the key board controlling the outlets.

Referring more particularly to the drawings, A designates a gasoline tank equipped with the usual filling pipe B, over-flow pipe C and drain D. Gasoline is delivered to the tank through pipe B until the tank is filled to its full capacity, as represented

by the dotted line or level F. All excess gasoline delivered to the tank during the filling operation is returned through the pipe C.

Generally speaking, my invention consists in providing means for controlling the discharge of gasoline from the tank to commence and end at a selected one of a series of predetermined discharge levels located below the gasoline level F and designated respectively by reference characters F', F², F³, F⁴ and F⁵. These discharge levels are uniformly spaced apart with the upper level F' located below the gasoline level F a distance exactly equal to the distance intervening between adjacent discharge levels. Preferably the spacing of the various levels referred to is such that when the gasoline is dispensed from the tank in successive discharging operations, occurring at the different discharge levels in the order of their arrangement, beginning with the level F', the quantity of gasoline released from the tank at each discharge will be exactly one gallon. As previously pointed out, discharge from the tank may be controlled to commence and end at any selected one of the several discharge levels and hence if it is desired to dispense three gallons from the tank in the initial discharge, the latter will be caused to occur at the discharge level F². It will thus be apparent that when the tank is filled to its full capacity, the contents thereof may be discharged in predetermined quantities ranging from one to five gallons.

In order to control discharge from the tank to take place at the different levels previously referred to, I provide the tank with a series of outlets designated 5, 5^a, 5^b, 5^c and 5^d. These outlets for the tank are in the form of casings shaped as shown in Fig. 2 and positioned in the tank one above the other. Each casing is provided with a top opening 6 and a bushing 7 threadedly engaged in said opening and having its lower end shaped to form a valve seat 8 normally engaged by a valve 9 which serves to close the opening to disrupt communication between the interior of the casing and the tank A. The upper extremities of the several bushings 7 are formed to present knife edges 7^a projecting above the top wall of the casing and contained respectively in the planes F', F², F³, F⁴ and F⁵.

Identical means are provided for selectively opening the several valves 9 and, as

herein shown, such means consist of a lever 15 mounted on an intermediate pivot 16 and formed with a forked extremity 17 straddling the valve stem 9 and resting on the cross pin 14. The remaining end of each lever is connected by a flexible strand or wire 18 to one of a series of keys 19. Each key is in the form of a lever having one extremity pivoted upon a shaft 20 and the other extremity equipped with a finger piece 21, the actuating wires being connected to the levers at any suitable point intermediate the shaft and finger piece. It will thus be apparent that upon depressing any selected one of said keys the valve connected therewith will be moved away from its seat to drain the tank down to the level coinciding with the knife edge 7^a of the bushing associated with the open valve. It is necessary that some means be provided for retaining the keys in depressed position and for this purpose, each key is passed through a slot 22 formed in the shell 23 supporting the tank A. At its lower end, each slot 22 is provided with a lateral extension 22' in which the key, operating in said slot is adapted to be secured to hold the key in depressed position. In order to provide for the lateral movement of the keys necessary to engage the same in the extensions 22' of the said slots, the ends of the keys mounted on the shaft 20 are provided with relatively large openings receiving the shaft therethrough so that the keys are capable of a slight lateral movement with respect to the shaft.

With reference to the mounting of the outlet casings in the tank A, it will be noted that the several casings are connected together by nipples 24 with the casing 5^d resting directly on the bottom of the tank and connected through an elbow 25 to the flexible delivery hose 26. Preferably, a cut-off 27 of the usual type is interposed in the connection between the elbow 25 and the delivery hose 26. The upper outlet casing 5 is connected by a vertical pipe 28 to one extremity of a U-shaped coupling 29 straddling the upper end of the tank. A guide tube 30, disposed exteriorly of the tank A, extends from the remaining extremity of coupling 29 to a point adjacent the keys 19. The several wires 18 extend from the levers 15 through nipples 24, pipe 28 and guide tube 30 to their respective keys. Preferably, casings 5, 5^a, 5^b, and 5^c are provided, as shown in Fig. 2, with guide staples 31 through which are carried the wires 18 from the casings positioned therebelow. In this way, fouling of the wires during selective operation of the valves is prevented. If desired, each wire 18 may be enclosed in an individual guide tube 18^a extending, as shown in Fig. 2, from the top casing 5 to the lower end of the main guide tube 30.

For convenience of operation, keys 19 are

consecutively numbered from 1 to 5, as indicated in Fig. 5, the key 1 being connected to the valve operating lever of casing 5; the key 2 to the valve operating lever of casing 5^a, and so on.

In explaining the complete operation, we will assume that tank A is charged to its full capacity, as represented by dotted line F, and that it is desired to dispense one gallon of gasoline. This is accomplished by depressing and engaging key 1 in the offset 22' of slot 22 whereby the valve 9 of casing 5 is withdrawn from engagement with its seat 8, thereby placing the interior of the casing in communication with the tank. The gasoline will now flow from the tank through casing 5 and nipples 24 to the delivery hose 23 until the level of gasoline in the tank is lowered to the point F' at which time further discharge from the tank will automatically terminate. By subsequently selecting any one of the remaining keys, further predetermined quantities of gasoline may be discharged from the tank ranging from one to four gallons. If, when the tank is filled to its capacity, it is desired to discharge five gallons or practically the full contents of the tank, this is accomplished by depressing the key connected to the valve contained in the outlet casing 5^d. It is thus apparent that by selective operation of the various keys, the contents of the tank may be dispensed at will in any predetermined quantity, ranging from one gallon to any multiple thereof within the capacity of the tank.

In order to seal the valves 9 against leakage when in closed position, I may provide the pipe 28 with an opening 28^a located a predetermined distance above the casing 5. In this modified structure, it will be apparent that when the tank is filled to its capacity, the level of the gasoline will be in the plane of said opening as a certain percentage of the gasoline will flow thru the opening to fill the nipples 24 and the several valve casings. It will be understood, in this connection, that the quantity of gasoline contained in the nipples 24 and in the valve casings added to the quantity of gasoline contained in the tank between the casing 5 and the opening 28^a will equal exactly one gallon.

While in the foregoing I have described what I now consider to be the preferred embodiment of the invention, it will be apparent that the same results could be accomplished by other means such for example as the provision of a single outlet adjustable within and in reference to the tank to dispose the receiving end of the outlet at any selected one of the discharge levels F', F^a, F^b, F^c, F^d or F^e. It will also be understood that various other changes in the construction and arrangement of parts may be resorted to within the scope of the appended

claims without departing from the spirit of the invention.

What I claim is:

1. A dispensing tank equipped with a series of vertically spaced outlets located therein, each of said outlets comprising a casing having an opening in its top wall for placing the interior of the casing in communication with the interior of the tank, a bushing fitted in said opening and having its upper extremity shaped to provide a knife edge surrounding and projecting above the opening, a valve normally seated against the lower end of said bushing to disrupt communication between the tank and the casing, and means for moving the valve away from said bushing.
2. A dispensing tank equipped with a series of vertically spaced outlets, each outlet consisting of a casing having an opening formed in its top wall and a valve normally closing said opening, nipples connecting the several casings together, a delivery pipe leading from the lowermost casing, a guide tube connected with the uppermost casing, a plurality of actuating levers, and actuating wires connected between said levers and said valves and passing through the guide tube.
3. A dispensing tank equipped with a series of vertically spaced outlets, each outlet consisting of a casing having an opening formed in its top wall, a valve normally closing said opening and formed with a depending valve stem having a pin passing transversely therethrough, a guide receiving the

lower end of said stem, a lever pivotally mounted within said casing and terminating at one end in a fork straddling the valve stem and overlying said pin, nipples connecting the several casings together, a delivery pipe leading from the lowermost casing and means for independently operating said levers to move the valves to open position.

4. A dispensing tank equipped with a series of vertically spaced outlets, each outlet consisting of a casing having an opening formed in its top wall, a bushing secured in said opening having its upper end formed to present a knife edge projecting above the casing and its lower end formed to provide a valve seat, a valve normally engaged with said seat and provided with a depending valve stem having a pin passing transversely therethrough, means for guiding the movement of said valve stem, a valve opening lever mounted in the casing on a pivot passing through an intermediate portion of the lever, one extremity of the lever being bifurcated to provide a fork straddling the valve stem and overlying said pin so that when the forked end of the lever is depressed it engages the pin to move the valve away from its seat, an operating element connected to the remaining end of the lever and a delivery pipe connected to all of said casings.

In testimony whereof I hereunto affix my signature.

MILTON G. VOLCKER.
